UNITED STATES PATENT OFFICE.

WILLIAM C. FIRTH, OF KANSAS CITY, MISSOURI.

ROWING-MACHINE.

1,217,292.

Specification of Letters Patent. Patented Feb. 27, 1917.

Application filed April 17, 1916. Serial No. 91,651.

To all whom it may concern:

Be it known that I, WILLIAM C. FIRTH, a citizen of the United States, residing at Kansas City, in the county of Jackson and 5 State of Missouri, have invented certain new and useful Improvements in Rowing-Machines, of which the following is a specification.

My invention relates to rowing machines, 10 and one feature of the invention resides in a novel arrangement whereby a fluid is employed as a resistant to the efforts of the oarsman.

Other features of the invention reside 15 in means for regulating the resistance of the fluid; means to indicate the number of pounds pulled by the oarsman at each stroke; and means to indicate the distance, or equivalent thereof, rowed by the oars- 20 man, or oarsmen.

A further feature resides in an attachment whereby the machine can be readily converted into use for two or any desired multiple of oarsmen, and in order that the 25 invention may be fully understood, reference will now be made to the accompanying drawings, in which:

Figure 1 is a plan view of the machine.

Fig. 2 is a broken plan view of certain 30 parts employed in carrying out the invention.

Fig. 3 is a side elevation of the machine.

Fig. 4 is an inverted plan view of the seat.

Fig. 5 is a vertical longitudinal section of 35 the machine on line V of Fig. 1.

Fig. 6 is a vertical section of a container on line VI of Fig. 5, with its lid removed.

Fig. 7 is a cross sectional view of the ma- 40 chine on line VII—VII of Fig. 1.

Fig. 8 is a plan view of the container and associated parts disclosed by Fig. 6.

Fig. 9 is a horizontal section of a pipe and retardant employed in carrying out the in- 45 vention.

Fig. 10 is a vertical section of a valve em- 50 ployed in carrying out the invention.

Fig. 11 is a plan view of an attachment for converting the apparatus into use by two or 55 more oarsmen.

Fig. 12 is a side elevation of the parts dis- 60 closed by Fig. 11.

Fig. 13 is a broken detail, enlarged, of 65 certain parts disclosed by Fig. 11.

In carrying out the invention, I employ 55 a suitable frame 1 mounted upon legs 2.

3 designates a transverse bracket secured upon the frame 1 and provided at its ends with bearings 4, in which crank arms 5 are mounted. The upper ends of the crank arms 60 5 have couplings 6 swiveled thereon and provided with a pair of mounted oars 7. In using the term "oars" throughout the specification I mean to include levers or other equivalents of the members 7. The bearings 4 are externally threaded to receive lock nuts A, whereby they are firmly secured to the bracket 3, after they have been adjusted 65 vertically to the desired height.

The lower ends of the crank arms 5 are 70 pivoted to connecting rods 8, which in turn are pivoted to the opposite ends of an equalizing bar 9 pivoted at its central portion to a plunger stem 10, connected at its forward end to a plunger 11 reciprocably 75 mounted in a fluid-containing cylinder 12 provided at one end with a stuffing box 13, to prevent leakage around said stem 10.

The opposite end of the cylinder 12 communi- 80 cates with a return-elbow 14 connected to one end of a tube 15, closed at its opposite end by a cap 16. The elbow 14, has a drain- 85 cock 14^a, through which fluid may be drawn off from the cylinder 12 and the tube 15. The cylinder 12 and the tube 15 are sup- 90 ported by the ends of the frame 1 and the bracket 3. The outer end of the plunger stem 10 is supported by a depending arm 17, slideable upon a guide rod 18 secured at its ends to arms 19 and 20, depending from 95 the cylinder 12 and the tube 15, respectively.

21 designates a small pipe leading from the tube 15 to a container 22 where it dis- 100 charges into a meter 23, the lower portion 95 of which extends into a cup 24 from which the fluid overflows into the lower portion of the container. The fluid in said cup 24 acts as a regulator for the meter 23, so that the operation of the same will be steady and accurate. The meter 23 is fixedly-mounted upon a shaft 25, provided with a pinion 26 to drive a large gear wheel 27, having a trip-pin 28 whereby a gong 29 is rung at each revolution of said gear wheel 27. The 105 gear wheel 27 is mounted upon a shaft 30, extending through the front wall of the container 22 and provided with a pointer 31,

which coacts with a dial 32 in registering the distance, or equivalent thereof, rowed by the oarsman. The pointer 31 may be adjusted to zero, or other predetermined point 5 preparatory to starting to row by a hand crank 33 fixed upon the rear end of the shaft 25, which extends through the rear wall of the container 22.

In order that the resistance of the fluid 10 against the plunger 11 may be regulated at will, I provide the small pipe 21 with a valve 34, having a valve plug 35 yieldingly-held to its seat by a spring 36, the pressure of which upon said valve plug 35 is manually 15 controlled through a screw 37, threaded through the upper portion of the valve and provided with a hand wheel 38. A check valve 39 on the pipe 21 prevents the fluid therein from flowing back into the tube 15. 20 40 designates a pressure gage to indicate the number of pounds pulled by the oarsman at each stroke. Said gage is actuated by fluid from a pipe 41 having an air-cushion 42 above the gage to steady the action 25 of the same. The lower end of the pipe 41, communicates with the tube 15 and its upper plugged end is secured to the rear wall of the container 22, to steady the same and prevent vibration. The lower portion of 30 the pipes 21 and 41 have drain-cocks 21^a and 41^a, respectively, to drain off the fluid above said cocks, when desired.

A time-clock 43 is supported beside the gage 40 on a solid bracket 44, extending 35 from a T-coupling 45 secured to the pipe 41. The indicators 32 and 40 and the time-clock 43 are disposed in front of the oarsman, so that they can be easily read during the rowing operation. One section of the pipe 41 40 has two perforated plates 46, between which gravel, or other retardant, 47, is placed to prevent the fluid from flowing too rapidly to the gage 40 and interfering with its proper operation.

45 48 designates an air-line communicating with the cylinder 12 at a point between the plunger 11 and the stuffing box 13, and leading to the container 22 to prevent air from becoming entrapped in the cylinder 12 and 50 offering variable resistance to the plunger 11. As the plunger 11 moves forward in the cylinder 12, air is drawn into the cylinder behind said plunger, and as the latter moves on its backward stroke the air is expelled 55 from the cylinder through the pipe 48, together, with any fluid that may have leaked behind the plunger. The lid of the container 22, has perforations 22^a, for free ingress and egress of the air.

60 49 designates a large return pipe leading from the bottom of the container 22 to the tube 15 to return the fluid thereto expelled through the pipe 21. A check valve 50 in the tube 15 prevents the fluid therein from 65 being forced back into the return pipe 49.

51 designates a seat for the oarsmen, which is provided with rollers 52 to traverse a pair of rails 53 mounted at one end upon blocks 54 and at their opposite end upon a yoke 55 secured to the frame 1.

56 designates a pair of pedals provided with straps 57 to secure the oarsman's feet upon said pedals, which are firmly secured to the tube 15 by a clamp 58.

In practice fluid, preferably, in the form 75 of oil is poured into the container 22 until it attains a level with the gage cock 22^b. As the fluid is poured into the container a portion flows down through the pipe 49, past the valve 50 and into the tube 15 and 80 the cylinder 12. After the cylinder 12 and the container 15 become filled with fluid a portion thereof flows into the pipe 41 and also into the pipe 21, until it attains a level in the latter on a line with the level of the 85 fluid in the container 22. The cup 24 is filled at the time that the container 22 is supplied with the fluid. The oarsman then takes his position upon the seat 51 and after adjusting his feet to the pedals 56, pulls 90 upon the oars 7 to advance the plunger 11. As the plunger 11 advances it forces fluid from the cylinder 12 into the container 22 through the tube 15 and the pipe 21, the check valve 39 of which latter prevents the 95 fluid from flowing backward therein. The fluid is discharged from the pipe 21 into the meter 23, and after acting on the same is discharged into the cup 24 from which it overflows. As the fluid overflows from the 100 cup 24 its level rises in the container 22 until the plunger 11 is forced on its backward stroke, whereupon a partial vacuum is formed in the cylinder 12, which, aided by the force of gravity, draws oil into said 105 cylinder 12, until the same is filled and the level of the fluid in the container 22 is reduced to normal. The check valve 50 permits the fluid in the pipe 49 to flow freely 110 from the container 22 into the tube 15, but prevents backward flow of the fluid. The reduced area of the pipe 21 retards the flow of fluid thereto, so that it will offer resistance to the advance stroke of the plunger 11. Should it be desired to increase the resistance 115 it is only necessary to adjust the valve 34 accordingly. As the return pipe 49 is of substantially the same diameter as the tube 15 and permits the fluid to return freely through said tube, little resistance is offered 120 to the backward stroke of the plunger 11.

Each forward stroke of the plunger 11 also forces fluid upward in the pipe 41 and creates a pressure upon the indicator 40, which registers the resistance offered by the 125 fluid against the advance of the plunger 11. As the air in the cylinder 12 is free to enter and leave through the pipe 48 during the operation of the piston 11, there will be little or no resistance from this source and 130

consequently the number of pounds pulled by the oarsman at each stroke can be accurately determined by the fluid pressure on the indicator 40. After the meter 23 has 5 made a predetermined number of revolutions, it, through the intermediacy of the gears 26 and 27, actuates the gong 29. Said meter also through the intermediacy of the pointer 31 and its coacting dial 32 indicates 10 the distance, or equivalent thereof, traversed, on each forward stroke of the plunger 11.

When two oarsmen are to be accommodated the attachment disclosed by Figs. 11 to 13, inclusive, is employed. This attachment 15 is substantially a duplicate of the mechanism already described, as indicated by the corresponding numerals with exponents. Hence, it is deemed unnecessary to go into detailed description thereof other than to state that 20 the attachment does not embody any of the fluid containing mechanism and indicators since the power exerted by both oarsmen acts upon the one plunger 11 and consequently duplication of said plunger, the cylinder 12, 25 the tube 15 and connecting parts is unnecessary.

As disclosed by Figs. 2 and 11, the outer end of the plunger stem 10 has a cross bar 60, to which a pair of extension rods 61 are 30 connected at their forward ends. Said extension rods 61 extend rearwardly of the frame 1 and are connected to a slidable member 62, mounted upon slide-ways 63, connected at their ends to a bracket 3^a and a 35 transverse rod 64, which latter is connected to the forward legs 2^a of the frame 1^a which is located at the rear and in line with the frame 1. An equalizing bar 9^a is pivotally-mounted upon the slidable member 62 and 40 connected to the crank arms 5^a through the intermediacy of a pair of connecting rods 8^a. The upper ends of the crank arms 5^a are connected to the oars 7^a by coupling members 6^a. With the foregoing arrangement 45 it is obvious that the power applied by oarsman number 2 is transmitted to the plunger 11 through the connecting mechanism above described.

If a third oarsman is to be accommodated 50 another pair of extension rods 61 are connected to the slidable member 62, which is provided with eyes 65 for that purpose. The last-mentioned extension rods are connected to a duplicate of the mechanism supported by the frame 1^a. Thus it will be 55 understood that extensions may be added to accommodate any desired number of oarsmen.

From the foregoing description, it is apparent 60 that I have produced an apparatus free from springs and other parts liable to get out of order, and while I have shown and described the preferred form of my invention, I reserve the right to make such 65 changes in the construction, combination

and arrangement of parts as properly fall within the spirit and scope of the claims.

Having thus described my invention, what I claim and desire to secure by Letters Patent, is:

1. In an apparatus of the character described, tubular means containing a fluid, a plunger reciprocably-mounted in said means and resisted in its action by the fluid, oars operably-connected to said plunger to 70 actuate the same, and indicating means actuated by the fluid to determine the distance rowed by the oarsman.

2. In an apparatus of the character described, tubular means containing a fluid, a plunger reciprocably-mounted in said means and resisted in its action by the fluid, oars operably-connected to said plunger to 80 actuate the same, indicating means actuated by the fluid to determine the distance rowed by the oarsman, and a signal actuated by said means.

3. In an apparatus of the character described, tubular means containing a fluid, a plunger reciprocably-mounted in said means and resisted in its action by the fluid, oars operably-connected to said plunger to 85 actuate the same, and a meter actuated by the fluid to determine the distance rowed by the oarsman.

4. In an apparatus of the character described, tubular means containing a fluid, a plunger reciprocably-mounted in said means and resisted in its action by the fluid, oars operably-connected to said plunger to 95 actuate the same, a meter actuated by the fluid to determine the distance rowed by the oarsman, and a gong controlled by said meter.

5. In an apparatus of the character described, tubular means containing a fluid, a plunger reciprocably-mounted in said means and resisted in its action by the fluid, oars operably-connected to said plunger to 105 actuate the same, indicating means communicating with the fluid containing means to determine the resistance offered by the fluid to the plunger, and a retardant in advance of said indicating means, for the purpose described.

6. In an apparatus of the character described, tubular means containing a fluid, a plunger reciprocably-mounted in said means and resisted in its action by the fluid, oars operably-connected to said plunger to 110 actuate the same, means extending rearwardly from the plunger, and oars operably-connected to said means.

7. In an apparatus of the character described, tubular means containing a fluid, 125 a plunger reciprocably-mounted in said means and resisted in its action by the fluid, a pair of oars operably-connected to said plunger to actuate the same, extension rods operably-connected to said plunger and ex- 130

tending rearwardly of the oars, and another pair of oars operably-connected to said extension rods.

8. In an apparatus of the character described, tubular means containing a fluid, a plunger reciprocably mounted in said means and resisted in its action by the fluid, a pair of oars operably-connected to said plunger to actuate the same, a seat adjacent 10 said oars, extension means operably-connect-

ed to the plunger and extending rearwardly thereof, another pair of oars operably-connected to said extension means, and a seat adjacent the last-mentioned oars.

In testimony whereof I affix my signature in the presence of two witnesses.

WILLIAM C. FIRTH.
